(57) **CLAIM**

The ornamental design for a chair frame, as shown and described.

DESCRIPTION

FIG. 1 is a front perspective view of a chair frame;
FIG. 2 is a rear perspective view of the chair frame of FIG.
1;
FIG. 3 is a front view of the chair frame of FIG. 1;
FIG. 4 is a back view of the chair frame of FIG. 1;
FIG. 5 is a right-side view of the chair frame of FIG. 1;
FIG. 6 is a left-side view of the chair frame of FIG. 1;
FIG. 7 is a top view of the chair frame of FIG. 1; and,
FIG. 8 is a bottom view of the chair frame of FIG. 1.
The broken lines shown in the drawings illustrate portions of
the chair frame that form no part of the claimed design.

1 Claim, 8 Drawing Sheets
